3 Claims. (Cl. 208—85)

The present application is a continuation-in-part of our copending application, U.S. Serial No. 254,741, filed November 3, 1951, now abandoned, entitled "Process for the Production of Benzene."

This invention relates to a process for the production of aromatic hydrocarbons. More particularly, it relates to a process for the conversion of petroleum hydrocarbon fractions rich in normal paraffin and naphthenic hydrocarbons into products rich in aromatics.

Recent developments in the synthetic chemical industry have enormously increased the demand for aromatic hydrocarbons, especially benzene and toluene. The normal demand for these hydrocarbons has been augmented by very large new demands, relating to the preparation of synthetic rubber and various plastics. The usual sources of supply for these aromatics have been completely exhausted due to this increased demand, and a number of procedures for synthesizing aromatics have become commercially attractive. At the same time some of the more obvious chemical raw materials suitable for conversion into aromatics have themselves become more useful for other purposes. For example, cyclohexane, which is easily converted to benzene, is itself in great demand as a raw material for the manufacture of synthetic fibers. Various higher boiling alkyl benzenes which are easily purified such as orthoxylene or paraxylene have become valuable as raw materials for the manufacture of phthalic acid or terephthalic acid. The net result is that the aromatics and cyclohexane derivatives available in petroleum and coal tar stocks are no longer able to supply this demand, and attention has been increasingly directed to alternate feed stocks for the synthesis of aromatics.

As a result of intensive research in this field, it has been found possible to aromatize many paraffin hydrocarbons containing at least 6 carbon atoms in the longest straight chain. Thus, the recent development of highly active and selective aromatization catalysts of the alumina/chromia type, promoted with silica and potassium oxide such as those described by Kirshenbaum and Gilbert in the co-pending application Serial No. 106,874, has made the aromatization of normal hexane to benzene very attractive commercially. These catalysts, in a low pressure operation at about 900–1100° F. and zero to 100 p.s.i.g., feeding hydrogen at a 1/1 to 4/1 mol ratio, can convert a normal paraffinic stock such as n-hexane to a high yield of highly aromatic product with low coke production, particularly when the feed is low in alkyl pentane and alkyl cyclopentane derivatives. However, crude oils as well as naphtha refinery streams do not contain high concentrations of n-hexane. Consequently it is necessary to process a suitable refinery stream by distillation, extractive distillation or other suitable separation process to concentrate the normal hexane present.

Engineering developments in the construction of high-efficiency distillation equipment have made such operations possible on a large scale, but they are always costly. In the case of n-hexane, the boiling point relation-

ships and the formation of azeotropes are such that it is exceedingly difficult to prepare a n-hexane concentrate which is free of methylcyclopentane and benzene. Benzene in an aromatization feed stock is not particularly harmful, but methylcyclopentane is. There is thus a definite need for a process which is capable of producing a hexane concentrate suitable for use as an aromatization feed stock, without requiring the actual isolation of separate pure compounds.

As indicated above, the demand for specific hydrocarbons available from petroleum sources has brought into being plants containing highly efficient separating equipment, capable of resolving the lower boiling fractions of naphtha into certain pure compounds for which there is a ready market. In many cases, however, it has been found more economic to operate these highly efficient separating plants in such a manner as to concentrate hydrocarbons of a given type or given narrow boiling range, giving higher plant capacity with some compromise in the purity of the concentrate produced. Such equipment, for example, may be used to separate concentrates of straight chain hydrocarbons from other fractions consisting largely of branched chain hydrocarbons. The latter, or isoparaffin fractions, can then be used as motor fuel blending agents of enhanced anti-knock value, useful in the preparation of aviation gasoline base stocks. This is a typical case where the operation of the plant so as to get the maximum production of premium quality motor fuel, in terms of "barrel octane numbers" dictates the operation of the separation equipment so as to give somewhat less than the maximum concentration of isoparaffins and normal paraffins in the separate fractions.

The normal hexane concentrate from such a separation process may be considered, by way of illustration, as a potential feed stock for the production of benzene. Typical compositions of hexane streams which can be prepared when using a battery of 50 to 100 plate fractionating columns to effect the separation by simple distillation are shown in Table I.

TABLE I
COMPOSITION OF HEXANE STREAMS (n-C₆)

Compound, Vol. Percent	A	C
2-methylpentane	21.6	12.0
3-methylpentane	13.1	12.6
n-hexane	35.0	37.4
methylcyclopentane	22.1	22.7
benzene	8.2	6.5
2,4-dimethylpentane		2.1
cyclohexane		6.7

Stream A is typical of the so-called "n-hexane stream" obtained when the fractionating unit is being operated primarily to produce fractions suitable for use in aviation base stock. Stream C, slightly different in composition, represents the product obtained when operating primarily for the preparation of a cyclohexane concentrate.

Both these streams contain branched paraffins and methylcyclopentane as well as normal hexane, in spite of the fact that they are the product of an efficient and expensive distillation process. Before the n-hexane can be aromatized to benzene, it is highly desirable to separate it from all the pentane derivatives present. The branched paraffins, including the methylpentanes and dimethylpentanes, and methylcyclopentane all degrade under aromatizing conditions to give undesirably high yields of coke and gas.

The aromatization of normal hexane has the advantage of upgrading material which has low octane number and consequently not only produces benzene, but at the same time removes from the gasoline pool material having a

research octane number of only about 25. The aromatization may give yields of benzene of about 65 mol percent on feed. When applied to the readily available n-hexane concentrates the process is expensive, however, primarily because of a tendency towards excessive carbon yields and high gas loss. Thus even the most promising catalysts may give typical carbon yields of 5.5 wt. percent when feeding pure n-hexane in the absence of added hydrogen at 1000° F., 0.4 v./v./hr. and atmospheric pressure to produce about 55 mol percent benzene on feed. At the same time, some benzene is normally lost with the effluent hydrogen formed in the aromatization process. To recover all of this benzene is very expensive, and this loss is increased with an increase in the amount of hydrogen and other light gases formed or recycled in the process.

The tendencies toward both coke and gas formation are materially less when using pure normal paraffin as the feed than when the branched chain paraffin and cyclopentane homologues are present. Thus even at low severities, using the preferred potassium oxide-silica promoted chromia/alumina catalysts with a 2/1 mol ratio hydrogen dilution of the feed, a 35% conversion with n-hexane gives only 0.8% coke on feed as compared to 2.5% for 2-methylpentane or 7% for methylcyclopentane. Coke production from the three hydrocarbons is in the ratio of 1 to 3 to 9, and at the same time aromatic yields fall off markedly, in the ratio of about 1 to 0.33 to 0.25.

It is therefore economical with a mixed C₆ cut to carry out a preliminary separation to remove these homologues, and further concentrate the normal hexane in the feed stock. One of the most satisfactory methods of carrying out such a separation is to use a selective adsorbent capable of separating normal paraffins from isoparaffins and naphthenes. A particularly desirable adsorbent is a form of activated carbon or charcoal which is capable of separating normal paraffins from a mixed virgin naphtha fraction and at the same time recovering the aromatic hydrocarbons present. Other adsorbents may be useful, however, and as an example of such other adsorbents we refer to U.S. Patent 2,522,426, in which the patentee Black describes a process employing a synthetic calcium aluminum silicate capable of selectively separating straight chain aliphatics from branched chain and cyclic hydrocarbons.

The selective adsorption process, however, has its own disadvantages, chief among which are the cost and possible side effects of the stripping medium and the cost of heating, cooling and reheating the process stream when it is to be employed finally as a feed stock for aromatization. Economic studies indicate that in the ordinary case where steam is used as the stripping medium in such a plant, most of the investment and operating costs are associated with the stripping step. Furthermore, with the preferred catalysts of the present invention, water is definitely harmful and the potassium oxide added to the silica-stabilized alumina gel is a strong promoter of the water gas shift reaction involving oxygenated compounds and hydrogen, so that ordinary "inert gases" such as steam or flue gas cannot be used for stripping in the feed preparation step without being entirely removed prior to the aromatization step.

It is an object of the present invention to prepare a feed stock for aromatization by selective adsorption without incurring the cost and undesirable effects of using steam or inert gas as a special stripping medium.

It is a further object to recover the normal paraffin and aromatic constituents of a naphtha feed stream by an adsorption process which requires no separation of the product concentrate from stripping medium.

It is also an object to prepare a feed concentrate for aromatization by adsorbing normal paraffins and aromatics together from a mixed hydrocarbon stream and desorbing them together, with a hot hydrogen-containing gas, to give a stripper effluent free of gases extraneous to the aromatization reaction.

It is a still further object to prepare such a concentrate by a process in which the cost of cooling a stripper effluent containing the stripping medium and then reheating the recovered desorbate is avoided, as is the loss of feed with discarded stripping medium. Other advantages of the process of our invention are derived from the fact that when a hydrogen-containing gas is used for stripping a higher stripping temperature may be employed without coking and tar formation on the adsorbent. This results in a more efficient desorption process, lower regeneration costs and a longer useful life for the adsorbent.

Our invention may be illustrated by reference to a process where normal hexane is concentrated from a C₆ naphtha fraction by selective adsorption on a steam-activated coke prepared from a petroleum acid sludge. The particular form of coke employed, known commercially as Chemico coke, is prepared by the steam activation of a carbonaceous residue obtained from a refinery sludge produced in the sulfuric acid treatment of high-boiling petroleum oils. This sludge, carbonized to recover its sulfur-containing constituents in the course of acid regeneration, gives as a by-product a light coke which is the source of the particular form of activated petroleum coke herein described. This carbonaceous residue is treated with steam or hot hydrogen at 1400-1600° F. to remove any residual material other than carbon, along with 15-50% of the original carbon in the coke. Instead of using steam it is also possible to use air or other suitable oxidizing gas. The best results in the use of this material in the process of the present invention are obtained when using a "high yield coke" where approximately 17% of the original carbon is taken out in the activation step. The resulting material is found to be highly selective for the separation of normal paraffinic hydrocarbons from isoparaffins or naphthenes. At the same time, it also adsorbs aromatic constituents of the original feed stock. Thus, a feed stock which consists entirely of naphthenes, aromatics and paraffin hydrocarbons may be treated with this material to recover an adsorbate consisting essentially of normal paraffin and aromatic constituents of the feed, while rejecting unadsorbed material consisting of the branched paraffins and naphthenes present.

According to the present invention the adsorbed material thus concentrated on the surface of the adsorbent is desorbed by using as a stripping medium the hydrogen-rich recycle gas produced by the aromatization of the normal paraffin instead of stripping with steam or other so-called inert gases. The harmful effect of steam as a contaminant in the aromatization process when using the particular catalysts here preferred appears in a marked decrease in the aromatic yield obtained in the presence of even small amounts of water vapor. Thus, over a 22% chromia catalyst promoted with 1.8% of potassium oxide and supported on an activated alumina gel containing 5% of silica, a particular hexane-rich feed containing about 48% n-C₆ and 7.5% methyl cyclopentane gives 53% benzene when aromatized at atmospheric pressure and 1025° F. in a water-free hydrogen atmosphere at 2/1 H₂/hydrocarbon dilution. The same feed, under the same conditions, gives only 41% benzene when 1.15 mol percent of H₂O is added to the feed; this falls off to 29% benzene when 6.2 mol percent of H₂O is present. The difference appears as an increase in olefins and unconverted feed. Exactly the same effect appears with pure n-hexane, where conditions which give a 50% yield of benzene in the absence of water vapor give only 35% benzene when 6.2 mol percent of H₂O is present.

Using n-hexane again for purposes of illustration, the normal hexane concentrate obtained in the adsorption step together with the stripping recycle gas used is then sent to the aromatization zone where n-hexane is converted to benzene with high selectivity. The operation of the process can best be understood by reference to the attached drawing.

A suitable refinery stream rich in n-hexane is supplied through line 1 to adsorption tower 2. This feed passes up through tower 2 countercurrent to a recycled stream of stripped adsorbent added through line 3. The adsorbent together with the adsorbate (primarily n-hexane and benzene) is passed by way of line 4 through heat exchanger 6 into stripping tower 12. The unadsorbed constituents in the feed leave tower 2 by way of line 5.

The stripper or desorption tower 12 which is shown here as a separate vessel may also be located immediately below the adsorption tower with a suitable means for supplying heat to the charged adsorbent, corresponding to exchanger 6, during passage from one zone to the other. In a particularly advantageous modification this supply of heat to the charged adsorbent is arranged so as to release a portion of the adsorbate which passes upward into the adsorption zone, as a reflux stream, below the level at which the fresh feed stream is introduced thereto. This reflux action can be controlled so as to result in an appreciable increase in the selectivity of the adsorption process.

In stripper 12, the heated adsorbent and remaining adsorbate enter downflow, in a direction countercurrent to the flow of a hot hydrogen-rich stripping gas entering the bottom of the tower through line 18. The desorbed n-hexane stream passes from the top of tower 12 together with the stripping gas, by way of line 20. This combined stream consisting essentially of hydrogen, normal hexane and benzene is passed directly to the aromatizing or hydroforming unit 22. The only gases present are reactants or recycled products of the aromatization process, and no oxygen-containing or inert gases are introduced at any point in the system which might cause undesirable side reactions or complicate the problem of ultimate product recovery.

Stripped adsorbent is withdrawn through line 14, suitably cooled by heat exchanging vessel 15, and returned by way of line 3 to the top of tower 2. Spent adsorbent may be removed from time to time or continuously as desired by way of valve 16 and line 17. Makeup adsorbent can be added as necessary through valve 8 and line 9.

The adsorption process in vessel 2 can be carried out either in the liquid phase or in the vapor phase. Vapor phase operation is preferred, partly because the separation factors or "alpha" values between the adsorption tendencies of the different types of hydrocarbons are found to be much greater under these circumstances. Thus both vessel 2 and vessel 12 may take the form of a bubble cap tower, where the adsorbent fluidized in the stream of rising gas flows down and over the successive plates in each vessel. This makes possible the effective use of small-sized particles of the order of 30 microns average diameter, with more rapid equilibration between the vapor and adsorbent than would be obtained when using a fixed bed or moving bed of larger granule size. Vapor phase operation also eliminates the expensive separation equipment such as filters or centrifuges which would be required for removing interstitial liquid from the adsorbent in the liquid phase process using suspended small particles.

The high selectivity of the activated petroleum coke here recommended for the vapor phase separation of normal from iso-paraffins is illustrated by the data shown in Table II, obtained on a 50/50 test blend of heptane/iso-octane:

TABLE II

Adsorption		Capacity, cc./100 g.	Separation (alpha) Factor
Phase	Temp., ° F.		
Liquid.....	80	27	7.6
Vapor.....	250	19.2	18

Adsorptive capacity is relatively little affected by the vapor phase operation, and these particular results are found after 28 cycles of alternating adsorption-desorption over the steam-activated coke. The very high separation factor realized here can be further pointed up by contrast with the more usual alpha factor of about 2.1 realized in liquid phase tests using the same binary blend with activated coconut charcoal as the adsorbent.

The adsorption step in vessel 2 is carried out preferably at a temperature only slightly above the dew point of the naphtha vapors introduced through line 1, since selectivity is found to drop as this temperature goes much above the dew point. A temperature of about 180°-200° F. is found to be satisfactory when feeding a C₆ cut at atmospheric pressure, and this might be changed to about 210°-230° F. when feeding a C₆-C₇ cut, as discussed in more detail below. The desorption in vessel 12 is carried out at a temperature between about 600°-900° F., preferably 800°-900° F., depending upon the nature of the various impurities present in the feed stream. Higher stripping temperatures give more rapid stripping, and the hydrogen-containing gas supplied through line 18 permits the use of such higher temperatures with minimum coke and gum formation during stripping.

The aromatization or hydroforming unit 22 operates under rather severe operating conditions of low pressure and high temperature. The pressure range may be 0-250 p.s.i.g., preferably 0-50 p.s.i.g., and the temperature range 650°-1150° F. preferably 900°-1050° F., using a highly active catalyst of the type of molybdena on alumina, molybdena on a zinc aluminate spinel, promoted chromia on alumina, or the like. The hydrogen introduced with the feed stream through line 20 may be in the H₂/feed mol ratio of about 1/1 to 10/1, preferably about 2/1 to 4/1.

The hydroformed product from the aromatization zone 22 passes by way of line 23 to fractionating unit 24. In certain cases this unit may consist of a group of fractionating towers, or a single tower may be used as shown in the diagram. The principal product stream 25 consists of benzene, which is higher boiling than the other C₆ hydrocarbons and lower molecular weight materials normally produced in the aromatization process. This benzene product stream, which may also include smaller amounts of heavier aromatics formed in the aromatization process, will ordinarily be recovered as a bottoms cut from the fractionator. A side stream 26 consisting of unreacted hexane and including normal hexenes formed during the aromatization process can also be recovered and recycled directly to hydroforming unit 22 by way of line 20. Stream 26 may also contain a certain amount of benzene, and any remaining C₆ naphthenes separated overhead from the benzene product in fractionator 24, all of which can be recycled to the aromatization process for ultimate conversion to benzene.

A lighter product stream 27 contains small amounts of C₄ and C₅ fractions produced during the aromatization. This stream 27 may also contain the lowest boiling of the C₆ hydrocarbons, including the dimethylbutanes, methylpentanes and small amounts of the corresponding lower boiling branched olefins. The constituents of this stream which are undesirable in the aromatization feed stream, all have a significantly higher octane number than the original n-hexane-rich feed stock. Thus it may advantageously be blended directly into the refinery gasoline pool, or it can be blended with other C₄-C₆ streams in the refinery. In other cases, it may be desirable to recycle a portion of stream 27 or a separate side stream not shown between line 26 and line 27 as feed to the adsorption step, by way of line 1, to recover an enriched n-hexane portion and separate the higher octane constituents therefrom by way of line 5.

The overhead stream 28 consists of a hydrogen-rich recycle gas including also a small amount of C₁-C₃ hydrocarbons. A portion of this gas is removed from the

system by way of line 30. Another portion, containing normally from 60 to 90 mol percent or more of hydrogen, is used as the stripping agent introduced through line 18 into tower 12 and recycled therefrom as a diluent gas for the aromatization process in vessel 22. A suitable heating means, shown diagrammatically as heat exchanger 32 is provided to raise the temperature of this stream to the desired temperature for use as a stripping gas.

The aromatic stream 25, consisting essentially of benzene with small amounts of heavier aromatic impurities, can be used as such or further purified by methods well known in the art.

The advantages of our process may be further seen from the following examples and experimental data:

Example 1

N-hexane was passed over a promoted $\text{Al}_2\text{O}_3\text{-CrO}_3$ catalyst, having the nominal composition 100 parts by weight of a commercial activated alumina carrier containing 5% of SiO_2 , together with catalytic oxides corresponding on an elemental analysis basis relative to the carrier of 11 parts of Cr, 0.86 Ce and 1.13 K. The reaction was carried out at 1000° F.; 0.4 v./v./hr.; 0 p.s.i.g.; and 2/1 $\text{H}_2/\text{n-C}_6$ mol. ratio. A once-through yield of benzene of 47 mol. % on feed was obtained. The carbon yield was only 2 wt. % of feed. With complete recycle of the C_6 fraction in the product, the benzene yield increased to about 74 mol. percent with the carbon yield being only 3 wt. percent on feed.

In a similar experiment but with no hydrogen recycle the once-through yield was 56 mol. percent but the carbon yield was 5.5%. On recycle the carbon yield increased to 7% while the aromatics yield was only 71%. It is thus apparent that in our process the ultimate benzene yield is higher (74 vs. 71 mol. percent) and the carbon yield lower than in conventional aromatization without H_2 recycle.

Example 2

Using a highly active catalyst comprising 1.8% potassium oxide as K_2O , from the nitrate, and 22% Cr_2O_3 added to a silica-promoted activated alumina gel containing about 5% SiO_2 , n-hexane conversions in the range of 75 to 95% can be obtained to yield 50 to 70 wt. percent of benzene without excessive degradation of the feed. The following correlated yields are found, in atmospheric pressure aromatization at a 2/1 hydrogen dilution, in the operating range of about 1000-1030° F. at an 0.2-0.5 liquid v./v. feed rate:

TABLE III

n-C ₆ Conversion, wt. Percent.....	75	85	95
Yields, wt. Percent:			
Aromatics.....	49	58.5	68.5
Carbon.....	0.6	0.9	1.1
C ₆ +Liquid Product:			
Vol. Percent on Feed.....	74.5	70	65.5
Benzene, vol. Percent.....	48	62	76
Toluene+Xylene, vol. Percent.....	0.2	0.2	0.4
Olefins, vol. Percent.....	15	14	12
Yield, Percent of Theoretical:			
Benzene.....	72	76	80

These results show the clear advantage of using the highly active catalysts preferred for the practice of the present invention, with a feed stock containing a high proportion of normal paraffin.

The advantage of using H_2 recycle gas in the adsorption stripping step may be seen from the following example:

Example 3

In commercial operation, 5250 barrels per day of the n-hexane stream, from a refinery battery of 50-100 plate naphtha fractionating unit, having the composition 29.4% methylpentanes, 36.3% n-hexane, 7.3% benzene, 1.1% dimethylpentane and the remainder methylcyclopentane

and cyclohexane are separated by adsorption on Chemico coke activated to 83% of its initial content. The products formed provide 2260 barrels per day of a n-hexane stream having the composition: 79% n-hexane, 16% benzene and 5% branched paraffins and naphthenes, and 2990 barrels per day of an isoparaffin-naphthene rich fraction containing only 5% n-hexane and benzene. This latter stream is blended into the motor gasoline pool while the n-hexane stream is sent to the hydroforming unit. In this adsorption operation, the Chemico coke circulation rate is 155 tons per hour and 330 thousand cu. ft. of H_2 rich (80-95% H_2) recycle gas from the hydroformer is used per hour as stripping agent. The n-hexane, benzene and stripping agent are circulated to the low pressure hydroforming unit operating at about 6 p.s.i.g., 0.4 v./v./hr. and 1000° F. As a result of this operation there are formed 1300 barrels/day of benzene (including the benzene in the feed), about 800 barrels per day of a C_6 fraction for recycle to the hydroformer, as well as 30 thousand lbs. of C_4 and C_5 per day.

While the process of our invention has been described specifically with reference to its application to the treatment of a hexane cut for the preparation of benzene, the same principle may be employed to advantage in the treatment of other normal paraffin fractions such as a heptane cut to be used in the preparation of toluene. The boiling point relationships in the C_7 and C_6 cuts are somewhat analogous, in that the alkyl cyclopentanes are in both cases much lower boiling than the corresponding cyclohexanes. Thus, a heptane cut chosen on the low boiling side of methylcyclohexane may contain most of the heptane of the original naphtha and most of the alkyl cyclopentanes.

The selectivity of the preferred activated coke adsorbent is such that the next most readily adsorbed hydrocarbons from this mixture after toluene and heptane are the methylhexanes, which are not nearly as objectionable in the aromatization feed stock as are the methylpentanes in the C_6 cut. To the extent that the methylhexanes can be retained in the adsorbate without contaminating the product undesirably with more highly branched paraffins, the operating conditions of the adsorbing process may be modified in this direction.

The process of our invention can likewise be applied to other paraffin-rich naphtha fractions, containing significant quantities of normal paraffin. It may be useful, for example, to prepare both benzene and toluene from a $\text{C}_6\text{-C}_7$ cut rich in n-hexane and n-heptane. It can be similarly employed to prepare xylenes from an octane cut, or in various other combinations to produce any of the lower-boiling monocyclic aromatics from the corresponding paraffin-naphthene cuts.

It will also be understood that while the process has been described primarily in terms of its application to a saturated naphtha fraction such as virgin naphtha, precisely the same treatment may be applied to a hydrocarbon fraction which has been catalytically converted to increase the content of more valuable hydrocarbons. The process may also be applied to advantage to various olefin-containing cuts where the concentration of straight chain aliphatic hydrocarbons is high, including both paraffins and olefins. Where olefin concentration is low it may be preferable to acid treat to remove olefins, avoiding any potential complications due to the tendency of olefins adsorbed on the activated carbon or other adsorbent used to polymerize thereon during the desorption step. The branched chain olefins, which polymerize most readily under the influence of heat, are also the most readily removed by such an acid treatment. The straight chain olefins such as the normal hexenes or heptenes are good feed stocks for catalytic aromatization, and will be retained in the aromatization feed stock where such a stream is treated according to the present invention. Under other conditions it may be desirable to prehydrogenate an olefinic stream before subjecting it to the cat-

alytic aromatization step. On the other hand, it may be most economical to process the olefinic stream concerned by feeding it directly to the selective adsorption step, making up for any decrease in adsorbent capacity by a corresponding increase in the rate at which spent adsorbent is discharged and fresh make-up added to the adsorbent cycle. This type of operation is particularly favored by the use of the hydrogen-rich stripping gas of the present invention. Any of these methods may be applied to a recycle stream of C_6 hydrocarbons from the final benzene purification step, as outlined above, or this stream may be split as shown by simple distillation into a branched chain paraffin-olefin concentrate to be sent to gasoline blending and a straight chain paraffin-olefin concentrate to be recycled directly to the catalytic aromatization.

The particular naphtha chosen as feed for this process may be one derived directly from crude distillation, or it may be any of various refinery process streams. Thus it may, for example, have been subjected to various preliminary treatments, such as hydroforming, isomerization, alkylation, or selective dehydrogenation, to selectively remove or alter the relationship between various hydrocarbons present. The principal requirement is only that the feed stream contain a significant proportion of normal paraffin, and be free of objectionable quantities of constituents which would polymerize during the adsorption-desorption process in spite of the use of hot hydrogen as the stripping medium.

What is claimed is:

1. The process for preparing an aromatic hydrocarbon from a narrow-boiling virgin naphtha cut rich in normal paraffin which comprises vaporizing a stream of said naphtha, passing said vapor stream upwardly through an adsorption zone in countercurrent contact with a moving stream of an activated carbon prepared from petroleum coke and highly selective for adsorbing normal paraffins together with aromatic hydrocarbons in the presence of branched paraffins and naphthenes, removing adsorbent and adsorbate from the bottom of the adsorption zone and a separate stream enriched in unadsorbed branched paraffins and naphthenes from the top of said zone, passing the said adsorbent and the adsorbate to a stripping zone where it passes downward countercurrent to a stream of hot hydrogen containing gas, stripping normal paraffin and aromatic adsorbate from the adsorbent in said hot gas stream, at a temperature of at least 600° F., cooling and recycling said stripped adsorbent to the adsorption zone, passing said hot gas stream comprising a reactant mixture of hydrogen, stripped normal paraffin and aromatic hydrocarbons to a catalytic aromatization zone to convert said normal paraffin to the corresponding aromatic hydrocarbon and additional hydrogen in the substantial absence of added gas extraneous to the reaction, and recycling hot hydrogen containing gas from said aromatization process at a temperature in excess of 600° F. as the hot stripping gas in said stripping zone.

2. The process of preparing from a n-paraffin rich hydrocarbon stream a feed stock for catalytic aromatization which comprises maintaining a circulating fluidized stream of a finely divided activated carbon prepared from petroleum coke and capable of selectively adsorbing normal paraffins and aromatics from a mixture of saturated and aromatic hydrocarbons and releasing said adsorbed hydrocarbons on subsequent heating and stripping, vaporiz-

ing said hydrocarbon stream and feeding said vapors upwardly at substantially atmospheric pressure into an adsorption zone countercurrent to a descending stream of stripped carbon adsorbent whereby said rising vapors assist in maintaining the mobility of said fluidized carbon stream, rejecting from the upper portion of said adsorption zone a raffinate comprising branched paraffins and naphthenic constituents of said feed stream, removing charged adsorbent from the bottom of the adsorption zone and passing said adsorbent with adsorbate downwardly through a stripping zone, at a temperature in excess of 600° F. countercurrent to a rising stream of a hot hydrogen-containing stripping gas at a temperature between about 650° and 900° F., whereby said rising vapors assist in maintaining the mobility of the fluidized carbon stream, removing a hot fluid stream of stripped carbon from the bottom of the stripping zone, cooling said fluid stream to approximately the desired adsorption temperature and recycling the thus cooled adsorbent to the adsorption zone, removing overhead from the stripping zone a hot stream of combined hydrogen-containing stripping gas and desorbed normal paraffin and aromatic constituents of the original feed stream, free of other added gases extraneous to the aromatization reaction; passing said combined stream directly to a catalytic aromatization zone in the presence of a potassium oxide-promoted catalyst under severe conditions of low pressure hydroforming, recovering from said aromatization zone a product rich in aromatics and a gaseous stream rich in hydrogen, reheating at least a portion of said hydrogen-rich gas stream as stripping gas to the desorption zone.

3. The process for manufacturing aromatic hydrocarbons which comprises vaporizing a naphtha fraction containing normal paraffins in the C_6 - C_7 boiling range together with aromatic, naphthenic, and isoparaffinic hydrocarbons, passing said vapors at a temperature of about 180°-250° F. over an adsorbent carbon highly selective to the separation of normal from isoparaffins, thereby selectively adsorbing a hydrocarbon fraction enriched in normal paraffin and aromatic compounds and recovering therefrom a stream of unadsorbed hydrocarbon enriched in naphthenic and isoparaffin compounds, desorbing said n-paraffin and aromatic compounds together by stripping the charged adsorbent with a hot hydrogen-containing recycle gas at a temperature of about 600°-900° F., passing the resultant hot reactant stream comprising normal paraffinic hydrocarbon and hydrogen into a low pressure catalytic aromatization zone employing a potassium oxide promoted catalyst in the absence of any added gas extraneous to the aromatization reaction, recovering from said aromatization zone a product rich in aromatics and a gaseous stream rich in hydrogen, and recycling at least a portion of said hydrogen-rich gas as stripping gas for the desorption.
